[57] CLAIM

The ornamental design for a bezel for server, as shown and described.

DESCRIPTION

FIG. 1 is a perspective view of a bezel for server showing my new design;

FIG. 2 is a front elevation view thereof;

FIG. 3 is a right and left side elevation view thereof;

FIG. 4 is a top plan view thereof; and,

FIG. 5 is a bottom plan view thereof.

The broken lines are shown in the views for illustrative purposes only and form no part of the claimed design.
